[57] CLAIM

The ornamental design for a casserole or similar article, as shown.

DESCRIPTION

FIG. 1 is a side elevational view partly in section of a casserole or similar article showing our new design taken along the discontinuous section line 1—1 of FIG. 3;

FIG. 2 is a side elevational view thereof taken in the direction of arrow 2 of FIG. 1;

FIG. 3 is a top plan view thereof; and

FIG. 4 is a bottom plan view thereof.
